Fig. 1

Fig. 2

To all whom it may concern:

Be it known that I, Henriette Simon, a citizen of the United States of America, residing in New York city, county of New York and State of New York, have invented a new, original, and ornamental Design for a Heel, of which the following is a specification, reference being had to the accompanying drawing, forming part thereof.

Fig. 1 is a front perspective view of a heel showing my new design.

Fig. 2 is a side elevational view of the heel as shown in Fig. 1.

My design for a heel is characterized by the specific configuration thereof as best illustrated in Fig. 2.

I claim:

The ornamental design for a heel, substantially as shown and described.
